UNITED STATES PATENT OFFICE.

ROBERT FRANCIS COLBORNE, OF STRATHFIELD, NEAR SYDNEY, NEW SOUTH WALES,
AUSTRALIA.

SHUNTER'S HAND-ACTUATED AIR-BRAKE VALVE.

1,094,426.

Specification of Letters Patent.

Patented Apr. 28, 1914.

Application filed July 31, 1912. Serial No. 712,386.

To all whom it may concern:

Be it known that I, ROBERT FRANCIS COLBORNE, a citizen of the Commonwealth of Australia, residing at Redmyre Road, 5 Strathfield, near Sydney, in the State of New South Wales, Commonwealth of Australia, have invented a new and useful Shunter's Hand-Actuated Air-Brake Valve, of which the following is a specification.

10 This invention is designed for the purpose of providing a valve attachment to the Westinghouse triple valve, either of the quick acting or ordinary type, at present in use for controlling the movement of rail- 15 way and tramway brakes, which will enable the shunter to apply the brakes from either side of a railway vehicle while the same is moving, by operating an attachment thereon.

The invention is alike serviceable in cases 20 where single or double cylinders inclosing springs which put off the brake are used, and cylinders where the springs are dispensed with and the air used for putting off the brake, the former being the kind set out 25 in this specification.

The valve attachment is intended to dispense with the existing cover with its spring-seated separate graduating stem and graduating stem guide, which are placed adjacent to the main piston of a Westinghouse 30 triple valve, and provide only for the ingress of the compressed air to said piston from the main pipe. The substituted valve attachment has a casing or cover divided into three 35 compartments. The one contains a disk valve for opening and shutting the ports leading to the other compartments which are in communication through the medium of a double stop cock with the usual brake 40 cylinder and reservoir. The port connecting with the cylinder, when uncovered, allows for the application of the brake, and the port connecting with the reservoir, when uncovered, allows for the release of 45 the brake, both movements being obtained consecutively by the action of the shunter. The rotary action of the disk valve is governed by the movement of a spring controlled spindle lever, and the graduating 50 stem for operating the main piston of the triple valve, in order to restore it to its normal position, is arranged to be set in motion by a chamber lever attached to and rotating with the disk valve, the necessary 55 movements being made by the shunter.

Referring to the accompanying drawings, which form part of this specification: Figure 1 is a vertical central sectional elevation of the compartment or chamber containing the disk valve with its chamber lever, for 60 operating the graduating stem which is attached to the main piston of the Westinghouse triple valve. The disk valve, chamber lever, graduating stem, and spring controlled spindle lever are shown in their normal positions when the main piston is seated. The ports which connect with the cylinder and the reservoir, which are shown dotted, are covered by the disk valve. The double stop cock is shown in elevation. Fig. 2 70 is an elevation of Fig. 1, with cover in position on disk valve and graduating stem compartment. Fig. 3 is a vertical sectional elevation on line *a—a* of Figs. 1 and 2, showing the three compartments, also spring controlled spindle lever and double stop cock in elevation. Fig. 4 is an elevation showing reverse side to Figs. 1 and 2, with spring controlled lever in its normal position as retained by coiled spring, also limitation 75 stops for same. Figs. 5, 6, and 7 are vertical, central, sectional elevations of disk valve compartment as in Fig. 1, but showing the rotary disk valve in three working positions, namely, (5) with valve set to partially uncover port to cylinder to obtain slight application of the brake, (6) with valve set to wholly uncover port to cylinder to obtain full application of the brake, (7) with valve set covering port to cylinder and wholly uncovering port to reservoir to release the 80 brake. The chamber lever, being at end of stroke, has returned graduating stem and main piston to normal position. In Figs. 5 and 6 the dotted lines indicate movement of 85 graduating stem. Fig. 8 is a vertical sectional elevation on line *b—b* of Fig. 3, showing compartments which connect with double stop cock, also ports leading from disk valve compartment, the valve chamber being 90 shown in elevation. Fig. 9 is a detail of the double stop cock in open position, shown partly in central, vertical, sectional elevation, but with cylinder and reservoir pipe connections and double chamber shown in 95 elevation. Fig. 10 is a central, vertical, sectional elevation on line *c—c* of Fig. 9, with cock open. Fig. 11 is a horizontal section on line *d—d* of Fig. 9, with cock in cut out 100 position. Fig. 12 is a plan showing the gen- 105 110

eral arrangement of the invention as applied to a Westinghouse triple valve, with the connections to brake cylinder and air pressure reservoir, with pressure gage added to reservoir, also brake actuating levers, main train pipe, branch pipe, and shunter's hand actuating appliance. Fig. 13 is a side elevation of Fig. 12. Fig. 14 is a vertical, sectional elevation, enlarged, showing valve attachment fitted to Westinghouse triple valve, with graduating stem attached to the main piston. A fragmentary part of the reservoir and internal tube is also shown. Fig. 15 is a vertical, sectional elevation showing the parts displaced by this invention, consisting of the existing cover with its spring-seated separate graduating stem and graduating stem guide, and thrust pin attached to main piston.

In order to apply this invention, the casing A, stem B, guide C, and thrust pin D which has previously formed part of the main piston E (Fig. 15), are dispensed with, and in place thereof I substitute the peculiarly constructed casing A¹, the graduating stem B¹ centrally attached to the piston E, and, the internal guide C¹, as in Fig. 14. The casing A¹, which is the valve compartment, is bolted to the body part F of the triple valve, and is provided with the inlet passage A² which is in communication with the union G through the medium of the usual cock H. The casing A¹ is pierced with the radial ports I and J leading respectively to compartments K and L which are in communication, through the medium of passages 1 and 2 in the double stop cock M, and pipes M¹ and M², with brake cylinder N and auxiliary reservoir O. The radial ports I and J are opened and shut by the disk valve P, to which is attached the chamber lever P² used for operating the graduating stem B¹. This chamber A¹ is provided with the access cover A³, secured with transverse bolts A⁴. The valve stem P¹ is provided with the actuating lever Q secured to its outer end. The coiled spring Q¹ keeps the valve P against its seat by its outward pressure against the collar R. The extension ends Q² and Q³ are carried down to either side of the radial stop K¹, which is used to retain one of the prolongations while the other moves as the lever is operated. In Figs. 1, 2, 3, 4, and 13, lever Q is shown in its normal position when ports I and J are closed as in Fig. 1. In Fig. 13 the said lever Q is shown attached to the connecting rod S operated by shaft lever S¹ secured to the transverse spindle T supported in bearings on both sides of the vehicle and having on its extremities rope levers U. To complete the operating connections, similar levers U¹, attached to short spindles T¹, are also placed on each side of the vehicle. The ropes V are fastened to their extremities,

and are provided with operating handles V¹ for the shunter's use.

In Fig. 12, the floating brake lever W, attached to the usual cross head N¹, and the anchored lever W¹, are shown merely as part of the usual brake system.

The main air pipe X and branch pipe X¹, connecting with the union G through the medium of the usual cock H, are the usual means employed for feeding the air through passages A² and F¹ past the piston E to the reservoir O, providing the valve P is in the position indicated in Fig. 1, which is the position of rest to which the actuating spring Q¹ always brings it by the action of the extension ends Q², when the shunter releases his hold on the actuating handle V¹.

The various positions to be occupied by the valve P when operated by the shunter either to apply or to put off the brake, are indicated in Figs. 5, 6, and 7. Fig. 1, being the normal position, ports I and J are both closed. In making a slight application of the brake, levers U and U¹ would be moved sufficiently to bring actuating lever Q to the mid position shown in Fig. 5, when port I would be partially opened. The changed position of the graduating stem is shown by dotted lines. To make a full application of the brake, further pressure on levers U and U¹ would bring lever Q to the position shown in Fig. 6, giving a full opening of port I, the stem being moved to the position indicated by dotted lines. During these two operations the air will be passing into compartment K through the lower passage 1 in stop cock M and by pipe M¹ to brake cylinder N, causing a slight reduction of pressure in the main train pipe X, similar to that made when the vehicles are coupled together and the driver has to apply the brakes from the engine. In continuing the pressure on levers U and U¹, the extension end Q² of spring Q¹ would be brought against limitation stop Q⁴, thus indicating to the shunter the necessity for exerting further pressure until the end of lever Q is brought into contact with limitation stop Q⁵, insuring a greater rebound of spring Q², which, upon release of the shunter's handle, would carry lever Q back to the normal position indicated in Figs. 1 and 4, the extension end Q³, which is seated against the radial stop K¹ (shown dotted in Fig. 4) and causes the spring Q¹ to be compressed when the lever Q is moved toward its limiting stops thereby, offering the necessary resistance for the coiled spring Q¹ to cause the lever Q to rebound. In this operation, the graduating stem B¹ travels with the piston E, and will occupy a position as shown dotted in Fig. 6. The brakes would remain on until the shunter actuates the levers U and U¹ in the contrary direction, thus carrying lever Q up against the stop Q⁶, whereby valve P is ro-

tated so as to uncover port J, and chamber lever P² is brought in contact with the graduating stem B¹, which forces piston E back to its release position, as in Figs. 7 and 14, the air passing from reservoir O through pipe M² and port J into compartment casing A¹, thereby equalizing the pressure on both sides of the piston.

It is to be understood that the air supply needed to apply the brakes in the shunting of detached vehicles to which this invention has been fitted, is to be obtained from the residue remaining in the auxiliary reservoir O, and a pressure gage Y is attached thereto for the shunter's inspection. The direction taken by the air is indicated by the arrows at pipes M² and M¹, Figs. 12 and 13.

The double stop cock M is provided as a safeguard to cut out the valve attachment in the event of mishap or failure. In Fig. 11 it is shown in the cut out position, and when so adjusted, will allow of the triple valve acting in the ordinary way, the graduating stem B¹ moving freely to and fro with the main piston E because the chamber lever P² is normally free from contact with it, as indicated in Fig. 1. The compressed air would then be admitted by branch pipe X¹ through cock H and by passages A² and F¹ to piston E, and thence to other parts of the triple valve in the ordinary way. As long as the disk valve P remains in the position shown in Fig. 1, the mechanism of the triple valve is always available to be operated by the driver from the engine.

The graduating spring B³, confined between the guide C and collar B² fastened to graduating stem, is similar to the means provided in the Westinghouse triple valve for re-seating stem B, but in this invention, the stem, being attached to the piston, will always move with it, and not be operated intermittently as is the case with the Westinghouse stem (*vide* Fig. 15).

In Fig. 14 the principal parts of the Westinghouse quick acting triple valve, namely, main piston E, body part F, bottom part 3, piston stem 4, slide valve 5, ports 6 and 7 in body part, center piece 8, secondary piston 9, central valve and stem 10, check valve 11, cock handle 12, and union nipple G, are shown, together with a fragment of the auxiliary reservoir O which is in direct communication with the rear side of piston E through the opening O¹. The pipe O is also shown attached to the chamber of the secondary piston 9. It is through this pipe that the air is conveyed to the brake cylinder N in the Westinghouse system, but in this invention the air is applied to cylinder N by pipe M¹, with the result that levers W and W¹ are brought into action independently of the connecting pipe O². The said reservoir is supplied with air pressure of about seventy (70) lbs. per square inch,

which is fed into it when the piston E is in the position shown, through the grooves 13 and 14.

Having now described my invention, what I consider new and desire to secure by Letters Patent is:

1. A shunter's hand operated air brake valve attachment, comprising a valve compartment, an air inlet passage forming part of the said compartment and communicating therewith and to the main piston, a graduating stem guide forming part of the compartment, upper and lower radial ports communicating from the valve compartment to adjacent compartments separated from each other and forming part of the valve compartment and communicating respectively with the auxiliary reservoir and the brake cylinder, a rotary disk valve adapted to cover the said radial ports, a valve stem forming part of the disk valve located horizontally in the division between the compartments, an actuating lever attached to the outer end of the valve stem, a coiled spring located on the valve stem between the double chambers and the seating collar adjacent to the actuating lever, extension ends forming part of the coiled spring and arranged on either side of a radial stop, a radial stop, a limitation spring stop affixed externally to the double chambered part of the casing, a limitation stop to control the movement of the actuating lever when putting on the brake, a limitation stop to control the movement of the actuating lever when putting off the brake, a chamber lever forming part of the aforesaid disk valve disposed upon the outer face of the valve to be in line centrally with the graduating stem of the main piston which is operated by it, and, a valve compartment removable cover secured thereto by transverse casing bolts, as described and shown, and for the purposes set forth.

2. The combination with a quick acting triple valve, auxiliary air cylinder and brake cylinder, of a shunter's hand operated valve attachment comprising a valve casing having an air inlet passage leading thereto, and being in communication with said triple valve, a pair of separate compartments formed within said valve casing each provided with a radial port, a disk valve for opening and closing communication through said radial ports to the interior of said valve casing and means for operating the same, passages leading from said compartments respectively to the auxiliary reservoir and to the brake cylinder, and a common controlling means for opening and closing both of said passages, and means carried by said disk valve adapted to operate the graduating stem of the triple valve piston, substantially as described.

3. The combination with the main piston

- of quick acting brake apparatus having a
graduating stem axially attached to said pis-
ton and moving therewith, auxiliary air cyl-
inder and brake cylinder, of a shunter's
5 hand operated valve attachment comprising
a valve casing surrounding said graduating
stem and in communication with the main
valve, an air inlet for said valve casing, a
10 pair of separate compartments formed
within said valve casing and having radial
ports communicating with the interior of
said casing, a disk valve for opening and
closing said ports, means for operating said
disk valve, and means carried by said disk
15 valve for operating said graduating stem,
passages from said compartments to the
auxiliary reservoir and brake cylinder re-
spectively, and a common stop-cock for
opening and closing said passages simul-
20 taneously, substantially as described.
4. In a shunter's hand operated air brake

valve attachment the combination, with the
spring controlled actuating lever of a triple
chambered valve attachment, of the connect-
ing rod attached thereto, the shaft and con-
necting rod lever, the transverse spindle ex-
tending to both sides of the vehicle, rope
levers affixed to the extremities of the trans-
verse spindle, similar rope levers attached to
short spindles on both sides of the vehicle, 30
connecting ropes extending from lever to
lever, and operating handles affixed to the
ropes, as described and shown, and for the
purposes set forth.

In testimony whereof I have signed my 35
name to this specification in the presence of
two subscribing witnesses.

ROBERT FRANCIS COLBORNE.
